UNITED STATES PATENT OFFICE.

AXEL F. ERICKSON, OF AURORA, ILLINOIS, ASSIGNOR TO ALLSTEELEQUIP COMPANY, OF AURORA, ILLINOIS, A CORPORATION OF ILLINOIS.

STACKING TOTE BOX.

1,420,992.

Specification of Letters Patent. Patented June 27, 1922.

Application filed April 26, 1919. Serial No. 292,829.

To all whom it may concern:

Be it known that I, AXEL F. ERICKSON, a citizen of the United States, and a resident of Aurora, in the county of Kane and 5 State of Illinois, have invented certain new and useful Improvements in Stacking Tote Boxes, of which the following is a specification.

My invention relates to tote boxes which 10 are employed both in manufacturing and merchandising establishments for convenience in the handling, sorting and storage of quantities of articles of manufacture or merchandise.

15 The objects of my said invention are the production from sheet-metal of a strong and serviceable article of this character which will have sufficient strength and a suitable novel design to permit of any number 20 of such boxes being stacked, the one upon the other, thereby greatly facilitating their use in the storage of the articles handled in them, and which will also render them easier and more convenient for 25 manual transfer from place to place, individually. It will also be apparent from the description hereinafter made, taken in connection with the drawings, that my present design of box is extremely economical both 30 to fabricate and in the amount of material employed.

I prefer to attain the above enumerated objects by means of the structure illustrated in the accompanying drawing, in 35 which,—

Figure 1 is a perspective view of my improved tote box.

Figure 2 is a transverse section showing two boxes in stacked relation.

40 Figure 3 is a perspective view of one corner of the box.

Figure 4 is a longitudinal section of a box.

In the drawings I have employed similar 45 reference characters to designate the same parts throughout the divers views. The bottom 5, side walls, 6, 6, and rear and front walls 7 and 8 may be made from an integral blank of metal, or the bottom and the opposite side walls may be made of a single 50 blank and the front and rear walls or side walls as preferred, may be cut separately and secured to the bottom and adjacent walls by welding or in any other desirable manner. At a suitable distance from the

bottom, the side walls and front and rear walls are broken or bent outwardly at 9, and at a short distance therefrom are broken or bent upwardly at 10, so as to form the horizontal shelf or shoulder 11 between the 60 points 9 and 10. A suitable distance above the bend, at the point 10, the metal of the side, front and rear walls is folded outwardly and downwardly upon itself at 12. This outward fold 12, at the corners and 65 preferably throughout its entire extent, is spaced from the inner wall both to furnish additional stiffness to the structure and to furnish a channel 13 for the receipt of a reinforcing metal strap 14. The reinforcement may be in the form of a continuous 70 strap, as shown in Figure 1, or it may consist of right-angle corner pieces 15, which extend into the channels 13 and are suitably secured therein as shown in Figure 3. 75

The structure as thus described, by reason of the rigidity secured through the employment of the channeled upper edges in connection with the reinforcement strap or straps, may, by the use of material of suitable gage, be made as dependably strong as desired for any weight of material, but the style of construction above described permits the vertical walls of my box to be slightly inclined inwardly towards their 80 tops, which permits of the securing of greater strength without increasing the gage of the material employed and which also assists in bringing the horizontal shoulders or shelves 11 in a position to receive 85 a greater extent of the bottom of a similar tote-box which might be stacked thereon. I have indicated the relation of the inward inclination of the walls to their vertical disposition by means of the broken lines α 90 in Figure 2 of the drawings for the purpose of clearness.

For the purpose of further stiffening the structure and also for providing runners thereon, to facilitate sliding the boxes from 100 place to place, I provide longitudinally outwardly curved corrugations 16, 16, in the bottom, which are not extended sufficiently near to the ends of the box as to engage the shoulders 11 when the boxes are stacked. 105 These runners may be made of separate pieces 17, 17, and secured to the bottoms of the boxes by rivets or in any other suitable manner, if greater strength than is secured by the corrugations is desired. I have illus- 110

trated handles 18 secured either to the front or back, or both, of the boxes, which are of advantage, but in no wise necessary, as the presence of the shoulders 11 afford convenient means for grasping and lifting the box.

While I have herein illustrated and described certain specific means for carrying out my invention, it, of course, will be understood that I do not wish to be limited to the precise structure, for modifications or refinements thereof are possible without materially departing from the principles involved. I therefore desire it understood that such changes are contemplated as being within the scope of my appended claim.

What I claim as new is:—

A metal tote-box comprising a rectangular bottom, parallel reinforcing members extending longitudinally thereof to provide runners therefor, end and side walls arising from the longitudinal and transverse edges of said bottom; said walls being inclined inwardly toward their tops, L-shaped

flanges extending longitudinally along the upper portions of said walls the horizontal portions of which flanges providing outwardly extended shelves upon the four sides of the box whereby to support a superposed box and the vertical portions of said flanges being disposed at right angles to said shelves whereby to retain the superposed box against lateral movement, turned-back portions along the upper edges of said flanges providing U-shaped channels; said flanges being spaced from each other at their ends, and a strip of metal inserted in said channels and extended around the ends of the flanges to close the spaces between their ends.

Signed at Aurora, county of Kane and State of Illinois, this 31st day of March, 1919.

AXEL F. ERICKSON.
